UNITED STATES PATENT OFFICE.

GEORGE LEWIS PATTERSON, OF NEW YORK, N. Y., ASSIGNOR TO ALICE C. PATTERSON,
OF NEW YORK, N. Y.

BATTERY-HOLDER.

1,120,077.

Specification of Letters Patent.

Patented Dec. 8, 1914.

Application filed August 21, 1912, Serial No. 716,183. Renewed April 24, 1914. Serial No. 834,219.

To all whom it may concern:

Be it known that I, GEORGE L. PATTERSON, a citizen of the United States, residing at the city, county, and State of New York, have invented certain new and useful Improvements in Battery-Holders, of which the following is a full, clear, and exact description.

This invention relates to battery holders, and particularly to a unit system of battery holders which permits any number of units to be included in a series, and is possessed of numerous other advantages to be herein-after referred to.

15 In its broad aspect, the invention comprises a series of interconnected battery holding units and series terminals therefor.

A preferable embodiment of the invention is illustrated in the accompanying drawings, 20 in which—

Figure 1 is a view in side elevation of a series of interconnected units secured to a suitable support. Fig. 2 is a bottom plan view of the connected series, the battery 25 units being removed. Fig. 3 is a longitudinal vertical section of the series of unit holders. Fig. 4 is a fragmentary top plan view of two units, detached.

Referring to the drawings by numerals, 1 30 indicates a hinged shelf, or other suitable support, to which the series of connected units is attached. Each series of unit holders is provided with two terminal units 2 and 3, and a plurality of intermediate units 35 4, connected to said terminal units and to each other in the manner to be herein-after described.

Except for certain details of the series 40 terminal connections of the terminal unit holders, the construction of each of the units is the same, and I will therefore first describe features which they have in common and then the special connections of the terminal units.

45 Each unit comprises a head 5 of insulating material, preferably molded, and carries embedded, or otherwise secured therein, a bed plate 6 of horseshoe shape fitting over and inclosing a contact seat 7 formed or 50 molded in the head 4. Seated against the bed plate 6 is the top of a metallic casing 8 of the "can top" type, having its top recessed to correspond in shape with the bed plate 6 and having its lower end interiorly 55 threaded.

A spring tongue 9 of conducting material has one end 9^a thereof embedded in the insulated head 4, and extending from the side of the same for the purpose hereinafter described. The other end of this tongue extends over the contact seat 7 and has a V-shaped bridging contact end 10. A bridge plate 11, similar in shape to the bed plate and to the top of the threaded casing, is secured to said bed plate by the screws 60 shown, and supports both itself and the casing from the insulated head. Extending across said bridge plate and above the end of the spring tongue 9 is a metallic bridge 12. 65

The top of the insulated head 5 is preferably recessed, as at 15, at a point diametrically opposite the contact end 9^a of the spring contact to expose a portion of the bed plate 6. This bed plate at such 70 point is preferably provided with a screw-threaded aperture.

These unit holders, as described, are constructed for use with dry cells of the screw-top type shown in United States Letters 80 Patent No. 924,575, dated June 8th, 1909. These cells are provided at their upper ends with a threaded metallic sleeve 13 forming one electrode, and with a central metallic head 14 forming the other. When a cell of 85 this type is screwed into a unit holder, the head 14 contacts with the spring tongue 9 and forces the same from the bridge 12 with which it is normally thrown into contact by the spring of the tongue. The metallic sleeve 13 engages with the threads of the casing 8 as the battery is screwed up, and thus connects this terminal of the battery with the holder. The projecting end 9^a of the spring tongue, therefore, conducts 90 the current from one electrode of the battery, and the bed plate 6, being connected with the top of the casing 8, forms the other electrode terminal.

As I have before stated, these units are 100 formed with the tongue contacts 9^a and recesses 15 diametrically opposite each other. If, therefore, these units are assembled with their tongues 9^a inserted in the recesses 15 of the adjacent unit, and electrically connected thereto by a screw 16 and their recesses 15 are engaged by the tongue 9^a extending from the unit on the opposite side, these units will be connected in series electrically. 105

The terminal units 2 and 3 are similar in construction to the intermediate units, but differ in that their respective terminals, the tongue 9 in terminal unit 2 and the bed 5 plate 6 in terminal unit 3, are not exposed, but are embedded in an extension of the insulated head of the unit and appropriately connected with binding posts 17 forming the electrical service terminal connections 10 for the series.

The tongue contact extensions 9^a and the recess contacts 15 form aligned contacts, so that, in order to electrically connect the series of units, it is only necessary to insert the tongue of one in the recess of the adjacent unit and secure the two together by their screw 16. In addition to this electrical connection, I prefer to provide means for physically interconnecting the various 20 units of the series. To this end I provide each side of the insulated heads 5 with a dowel pin 18 and socket 19, these dowel pins and sockets in each head being positioned and aligned to cooperate with the sockets 25 and dowel pins of the adjacent unit heads. These physical connections for the units form in effect plug and socket connections and serve as a convenient means for physically uniting adjacent units so that their 30 electrical connections may be readily made. In addition, these plug and socket connections maintain the units in proper alignment and operate to prevent displacement. It will be seen from this that the process of 35 connecting up the various units is a very simple one, and that, when connected, they form a compact series of aligned units.

In order to attach these units to a suitable support, I prefer to provide each of 40 them with a number of apertures 20 formed in the insulated heads and adapted to receive a screw, bolt, or other attaching means, adapted for engagement with the support. I also prefer to space the units 45 from the support, and to this end provide the top of the insulated heads with spacing lugs 21.

It is believed that the cooperative relation 50 of the parts and the manner of forming an electrical connection by the insertion of the battery in the holder, is clear from the foregoing description. In addition, however, I may state that the specific form of battery contact described prevents the breaking of 55 the circuit by the removal of the battery as the spring tongue 9 will snap out upon the removal of the battery contact, and its V-shaped end 10 contact with the metallic bridge 12.

60 While I have illustrated a specific and preferable type of battery and battery contact, I do not desire it to be understood that the invention is only susceptible of use with these types of connections and batteries, but, on the contrary, consider it with-

in the spirit of my invention to modify the unit contacts and heads to accord with various types of battery units.

What I claim, therefore, and desire to secure by Letters Patent, is:

1. A battery holder comprising a series of cell holders, a base support for said holders, said base support being composed of detachable sections, with means for electrically interconnecting said cell holders 75 when the sections of said base are assembled.

2. A battery holder comprising a series of cell holders, a base support for said holders, said base support being composed of detachable sections, with means for physically connecting said sections, said physical connecting means also serving to electrically interconnect said cell holders. 80

3. A sectional unit battery holder comprising a series of electrically interconnected battery holding units, each unit being provided with battery terminal connections, the series being provided with service terminal connections. 85

4. A sectional unit battery holder comprising a series of physically and electrically interconnected battery holding units, each unit being provided with battery terminal connections, the series being provided 90 with service terminal connections.

5. A sectional unit battery holder comprising terminal units provided with electric service terminal connections, and a plurality of electrically interconnected intermediate 100 units in electrical connection with said terminal units, each unit being provided with battery terminal connections. 95

6. A sectional unit battery holder comprising terminal units provided with electric service terminal connections, and a plurality of physically and electrically interconnected intermediate units in physical and electrical connection with said terminal units, each unit being provided with battery 110 terminal connections.

7. A sectional unit battery holder comprising a series of interconnected battery holding units, each unit being provided with battery service terminals and with conductors therefrom engageable with the appropriate conductors of adjacent units when the series are assembled, and electrical service terminal connections for said series. 115

8. A sectional unit battery holder comprising a series of battery holding units, each unit being provided with battery service terminals and with conductors therefrom engageable with the appropriate conductors of adjacent units when the series 120 are assembled, electrical service terminal connections for said series, and means for physically interconnecting adjacent battery holding units. 125

9. A sectional unit battery holder com- 130

prising a series of aligned battery holding units, oppositely disposed contact terminals carried by each unit engaging respectively with the aligned contact terminals of adjacent units, battery terminal connections carried by each unit in electrical connection with the contact terminals thereof, and electric service terminal connections carried by the free terminals of the terminal battery unit holders.

10. A sectional unit battery holder comprising terminal battery holding units, each provided with electric service connections at one unit electrode terminal and with contact terminals respectively at the other unit electrode, a plurality of aligned intermediate battery holding units, each intermediate unit being provided with oppositely disposed contact terminals engaging respectively with the aligned contact terminals of adjacent units and of the terminal units, all battery holding units being provided with battery terminal connections in electrical connection with the unit contact terminals,

means for physically interconnecting the 25 battery holding units of the series, and means for attaching the series of connected units to a suitable support.

11. A sectional unit battery holder comprising a series of electrically interconnected battery holding units, electric service connections carried by the terminal units thereof, and a positioning and connecting member carried by each unit and coöperating with adjacent units to physically interconnect the series of holder units.

12. A sectional unit battery holder comprising a series of electrically interconnected battery holding units, electric service connections carried by the terminal units thereof, and a lining plug and socket connections between said units serving to position and physically interconnect said units relatively to each other.
